WEFT REPLENISHING PICK AND
PICK LOOMWalter H. Wakefield, Worcester, Mass., assignor
to Crompton & Knowles Loom Works, Worcester,
Mass., a corporation of Massachusetts

Application November 2, 1946, Serial No. 707,362

6 Claims. (Cl. 139—232)

1

This invention relates to improvements in weft replenishing pick and pick looms of the type having a weft detector on one side of the loom and replenishing mechanism on the opposite side, and in which three shuttles follow each other in rotation.

Looms of the type to which this invention relates ordinarily have shifting shuttle boxes with two cells on each end of the lay, the boxes shifting in four-pick cycles, each set or gang of boxes being up for two picks and then down for two picks, and the gangs shifting alternately so that one or the other of the gangs shifts each pick of the loom. The three shuttles are picked in such order that each shuttle, after being active for one pick is followed by another shuttle and becomes inactive for two picks. When a weft detector on the side of the loom opposite the magazine indicates exhaustion of weft in an inactive shuttle the greater part of four picks will elapse before the shuttle can be replenished. In order to carry over the indication until it can be used it has been necessary heretofore to employ holding means, such as a holding circuit for an electromagnet, or some form of lock which will retain the indication until the proper time arrives to release a bobbin for transfer and effect its transfer from a reserve bobbin magazine.

It is an important object of the present invention to provide improved weft detecting and bobbin releasing means including a cam operating on a two-pick cycle and effective not only to cause bobbin release from the magazine, but also provide the necessary time delay between indication of weft exhaustion when first given by the weft detector and the time when the indication can properly be used to initiate a two-pick sequence culminating in bobbin transfer.

The magazine ordinarily comprises bobbin stacks each having a delivery cradle controlled by an upright slide which is given a complete reciprocation by an actuator upon call for replenishment, moving first in an upward direction to turn the cradle to receive a bobbin from its stack, and then descending to turn the cradle in the opposite direction to release the bobbin so it can move to transfer position. An empty shuttle in the top shuttle box at the side of the loom opposite the magazine will be out of action or inactive for two picks, and will cause the detector to give an indication of exhaustion at the beginning of its period of inaction. When the shuttle returns to action two picks later it is picked to the magazine side of the loom and is then moved out of action for another period of two picks. The

2

shuttle will not be properly placed for transfer during the first pick of this second pair of picks but will be so placed during the second pick, and because of this fact the greater part of four picks lapses between first indication of exhaustion and replenishment.

It is a further object of the invention to provide an improved two-pick cam for the slide actuator operating in such manner that start of a two-pick replenishing sequence can be delayed until just before the depleted shuttle returns to action, thereby permitting the sequence to extend into the third and fourth picks of the aforesaid four-pick cycle. This arrangement avoids the use of a holding circuit if an electric detector is used, or other means for storing an indication of weft exhaustion over a period of more than two picks.

With these and other objects in view which will appear as the description proceeds, my invention resides in the combination and arrangement of parts hereinafter described and set forth.

In the accompanying drawings, wherein a convenient embodiment of my invention is set forth, Fig. 1 is a diagrammatic front elevation of a loom having the invention applied thereto.

Fig. 2 is an enlarged side elevation of the magazine looking in the direction of arrow 2, Fig. 1.

Fig. 3 is an enlarged diagrammatic view showing the cam as it would be seen from arrow 3, Fig. 1, and showing the actuator lever.

Fig. 4 is an enlarged elevation of the cam on the bottom shaft which operates the actuator.

Fig. 5 is a diagrammatic view of the electric circuit used with the invention, and

Fig. 6 is a series of diagrammatic views showing successive positions of the shuttle boxes and parts of the invention for four successive picks and part of a fifth pick, the figure being arranged with four vertical columns A-D showing different parts of the invention, and the successive lay positions being indicated by Roman numerals.

Referring particularly to Fig. 1, the loom frame 10 has a lay 11 which is reciprocated backwardly and forwardly in the usual manner. At the right end of the lay is a gang RG of two shuttle boxes or cells, the upper and lower of which are indicated at 12 and 13, respectively, while at the opposite side of the lay a second gang LG has top and bottom boxes or cells 14 and 15, respectively. The gangs RG and LG are supported, respectively, on box lifter rod 16 and 17 under control of shuttle box operating mechanism not shown. The gangs are each on a four-pick cycle, each gang being in high position for two suc-

sive picks to place the lower cell or box thereof in active position, and then in low position for the next two picks to place the top cell or shuttle box thereof in active position. One or the other of the gangs shifts every pick of the loom, the shifting of the gangs being out of step by one pick to accomplish this result.

The gangs of boxes cooperate with three shuttles S1, S2 and S3 which follow each other in rotation so that each shuttle after being active for one pick is moved out of action for the next two picks and is followed by another shuttle. The shuttles may all carry the same kind of filling, or the wefts of the shuttles may be diverse, in which event the replenishing mechanism will be adapted to supply reserve wefts corresponding to the wefts of the shuttles.

During a complete reciprocation the lay will pass through four major positions which are, respectively, bottom, front, top and back centers. The shuttle boxes shift when the lay is in the forward part of its motion between bottom and top centers and will ordinarily be half shifted when the lay is at front center.

The loom is provided with a multistack magazine M which in the present instance as shown in Fig. 2 provides four stacks 18, 19, 20 and 21 of reserve bobbins. Each stack is associated with a vertical or upright bobbin release member or slide, these members being indicated at 22, 23, 24 and 25. The lower end of each of these upright members is operatively connected to a cradle part of which is indicated at 26. Each member 22-25 has upper and lower lugs 27 and 28 respectively. The members 22-25 are normally down and the cradles are empty, but when any of the upright members is raised its corresponding cradle is rocked in one direction to receive a bobbin from the associated stack, and when the upright member is later depressed the cradle returns to its normal position to deliver the previously received bobbin. The latter thereupon moves to a transfer position designated at W under a transfer arm 30 having a transfer latch 31 for engagement with a bunter 32 on the gang RG.

The mechanism for raising and lowering the upright members includes a selector 35 which has rocking movements and also longitudinal movements so that it can register with the upright slides or members 22-25 one at a time. As shown in Fig. 2 the selector 35 is registered with the front upright slide 22 for cooperation with its lugs 27 and 28, but it can be moved rearwardly from the position shown in Fig. 2 by a positioning lever 36 operated by any approved form of control.

A stand 40 fixed with respect to the loom guides a vertically reciprocating block 41 the upper end of which is pivoted as at 42 to an actuator lever 43 between the ends thereof. One end of the lever is connected to an upright rod 44 which is connected to the selector 35 as at 45 and is the means by which the selector is rocked. The lower end of block 41 is connected to a descending rod 46 connected to a relatively large lever 47 pivoted on a fixed support 48. The rear part of lever 47, that is the right end as viewed in Fig. 3, carries a roll 49 to cooperate with a cam designated generally at 50. The cam is on the bottom shaft 51 of the loom and completes a rotation in two picks, turning in the direction of arrow a.

The right end of lever 43, Fig. 3, is adapted for cooperation with a fixed stud 55 thereover and a movable controller pin 56 thereunder. The pin 56 is slidable backwardly and forwardly in the

stand 40 and is under control of a solenoid 57 fixed to the loom frame. The core 58 of the solenoid is connected to the controller pin 56 as at 59. Ordinarily the core 58 and pin 56 are held to the left as viewed in Fig. 5 by means of a light compression spring 60 for the purpose of holding the rear end of the controller pin out of the vertical path of the adjacent end of actuator lever 43.

10 The details of cam 50 form the important part of the present invention and will be set forth more clearly hereinafter, but it may be stated that it gives lever 43 two characters of motion. The pivot 42 has a normal or neutral position during parts of the cycle of operations, but moves downwardly at periodic intervals and then returns to its neutral position, after which it rises and then returns to its neutral position. When the controller pin 56 is in its normal non-controlling position, the down motion of pivot 42 is idle in that the right end of lever 43, Fig. 3, descends without causing movement of rod 44 or angular movement of the selector 35. If, on the other hand, the controller pin is in indicating position, this normal idle movement of lever 43 is prevented and it rocks in a counter-clockwise direction, Fig. 3, around pin 56, thereby depressing rod 44 and rocking selector 35 in such direction as to raise the lug 27 of the upright slide 22-25 registered therewith.

30 The second of the motions imparted to pivot 42 by the cam 50 is upward and always causes lever 43 to move about fixed pin 55 as a center and of course causes rising of the rod 44 and rocking of selector 35 in the opposite direction, or in a direction to cause it to engage any raised lug 28 registered with it to lower the corresponding vertical slide. The downward and upward motions of pivot 42 from the neutral position thereof occur in regular sequence for each pair of picks of the loom, rising of rod 44 being regularly recurring once for each pair of picks, but depression of rod 44 occurring only when controller pin 56 is under lever 43.

45 The loom operates with a weft detector or feeler F of the electro-mechanical side slipping type mounted on an upward extension of the lay designated at 60 in position to engage the weft of the shuttle in cell or box 14 when the gang LG 50 is in its up or high position indicated in Fig. 1. If sufficient weft for continued weaving is present in shuttle box 14, the feeler will rise in usual manner without giving indication, but if the weft is depleted the detector arm 61 will rock in a counter-clockwise direction as viewed in Fig. 1 and engage an electric contact 62 fixed with respect to the lay.

55 The loom has a shipper handle 63 connected to a switch 64 which is closed when the shipper handle is in running position to cause loom operation, but open when the shipper handle moves to stopping position when loom operation is arrested.

65 When the detector indicates weft exhaustion the following detector circuit, Fig. 5, will be closed: secondary winding 65 of a transformer T, wire 66, switch 64, detector arm 61, contact 62, wire 67, wire 68, solenoid 57, and wire 69 back to the secondary winding 65. Closure of this circuit energizes solenoid 57 and causes rearward movement of its core 58 and also the controller pin 56 against the action of light compression spring 60. This energization of solenoid 57 will continue so long as a depleted weft supply in shuttle box 14 is in raised position, and during

this energization of the solenoid controller pin 56 will remain under the actuator lever 43. The feeler and contact 62 are suitably insulated from the lay in well known manner.

The sequence of operations for four successive picks of the loom are indicated in Fig. 6 which sets forth a series of diagrams grouped to show picks one to four, inclusive, of a four-pick cycle, each pick setting forth four lay positions and starting with the lay on bottom center. The positions of the lay are indicated by Roman numerals running consecutively from the first lay position of pick one through the last bottom center position of pick four. In order to complete the sequence part of the first pick of the next four-pick cycle is also shown, since it is in this position of the lay that transfer actually occurs. The various parts indicated in Fig. 6 are arranged in vertical columns as follows: column A, shuttle boxes and weft detector; column B, actuator lever and controller therefor; column C, lay bunter and transfer latch; and column D, selector and upright or vertical slides.

In position I of pick one gang LG is down with shuttles S1 and S2 in boxes 14 and 15, respectively, while gang RG is up with shuttle S3 in box 12, box 13 being empty. The lay is at bottom center and moving forwardly, and shuttle S1 has just entered box 14 and is assumed to be depleted of weft. Actuator lever 43 is in down motion, but controller pin 56 is forward and rod 44 therefore remains at rest and the selector 35 is in neutral position. The transfer latch 31 is in down or non-transfer position below the path of the shuttle box carried bunter 32.

In position II the lay is at front center and gang LG is rising to move exhausted shuttle S1 toward the detector or feeler F. Actuator lever 43 has returned to its neutral position, the bunter 32 has reached its foremost position, latch 31 is down, and selector 35 is still neutral.

In position III boxes LG are fully up and depleted shuttle S1 has rocked the feeler F to engage contact 62, thereby energizing the circuit shown in Fig. 5 and causing excitation of the solenoid with resultant movement of the controller pin 56 under lever 43. The latter is still in neutral position as is also the selector, the lay is at top center so that bunter 32 is moving rearwardly and shuttle S2 is about to be picked.

In position IV the lay is on back center with shuttle S2 moving toward box 13. The actuator lever and selector are still neutral. This completes pick one and leaves the controller pin 56 under the actuator lever, but otherwise no change has occurred in the replenishing mechanism.

Pick two starts with position V in which the lay is on bottom center and both gangs of boxes up. Lever 43 and selector 35 are still neutral.

In position VI the lay is again on front center and gang RG is descending, while the actuator lever and selector remain neutral.

In position VII the lay is at top center, gang RG is down and shuttle S3 is about to be picked. At or about this time cam 50 raises the actuator lever 43, thereby causing a clockwise rocking of selector 35 which, however, is idle since the vertical slide 22 is down.

In position VIII the lay is on back center with shuttle S3 approaching box 15, actuator lever 43 has returned to its neutral position as has also the selector 35. Thus far the vertical slide

22 is unmoved and since gang LG is still up the solenoid remains energized to hold controller pin 56 under lever 43. This completes pick two of the four-pick cycle and also the two-pick cycle of lever 43.

Pick three starts with position IX in which the lay is at bottom center and gang LG preparing to descend. Lever 43 is moved down by cam 50, but since controller pin 56 is still in controlling position due to continued energization of the solenoid as a result of gang LG remaining up, rod 44 is depressed and the selector 35 is given a counter-clockwise angular movement, thereby engaging top lug 27 of slide 22 to lift the latter. This stores an indication in the magazine inasmuch as the slide 22 when moved to its up position will remain there until subsequently depressed. During upward movement of slide 22, however, the transfer latch is un-affected and remains down.

In position X the lay is on front center for the third time and boxes LG are moving down, shuttle S1 having left the feeler F and thereby breaking the circuit on the solenoid. Controller pin 56 therefore returns to its forward position clear of the actuator. Lever 43 and the selector are in their neutral positions, and slide 22 is still up.

In position XI the lay is at top center with shuttle S1 about to be picked. The actuator lever and selector are still in neutral position.

In position XII shuttle S1 approaches shuttle box 12 as the lay is on back center, the actuator lever and selector remaining neutral. This completes pick three.

Pick four starts at position XIII with the lay again on bottom center and advancing, the actuator lever and selector remaining neutral.

In position XIV gang RG is rising to move shuttle S1 to its up position where it can receive the incoming reserve bobbin. The actuator lever and selector are still neutral, and slide 22 is still up.

The magazine generally employs parts not shown herein to effect resetting of the magazine incident to completion of a transfer operation by forward movement of the lay. Obviously, the magazine cannot be set for transfer when the lay is at front center since this is the condition of resetting, but at some time subsequent to position XIV, such as position XV after the lay has left front center, as at top center, the magazine can be set for transfer, and at this time the cam 50 will again raise actuator lever 43 which will have the effect of rocking selector 35 in a clockwise direction, thereby depressing the previously raised slide 22 by engagement of lug 28 thereof. This has the effect of raising the transfer latch 31 to transfer position and also releasing a bobbin from the front stack so that it can move to the transfer position W. Bunter 32 is moving rearwardly at this time, hence latch 31 is able to rise, and shuttle S2 is about to be picked from box 13. The magazine is now set for transfer.

In position XVI the lay is at back center with shuttle S2 approaching box 14, having left box 13 empty for discharge of the depleted bobbin in shuttle S1. Actuator lever 43 and selector 35 are back to their neutral positions and latch 31 awaits operation by bunter 32.

This completes pick four and also the four-pick cycle of movements of the shuttle boxes, and completes also the second two-pick cycle of actuator lever 43. To indicate how transfer is

actually effected, Fig. 6 shows the first two positions of the ensuing pick five.

In position XVII the lay is on bottom center position of pick five, a second four-pick cycle starting with this position XVII. The actuator lever 43 descends as it did in position I, but gang LG is down so that the weft feeler F cannot close the detector circuit, hence the controller pin 56 is necessarily forward and cannot trip lever 43, and selector 35 remains neutral. It is the existence of these same conditions at or immediately before position I which prevented rising of slide 22 during pick one.

In position XVIII the lay has reached front center position, bunter 32 has moved latch 31 forwardly and the transerrer arm 30 has been rocked to depress the bobbin W into shuttle S1, the exhausted bobbin descending through box 13. This completes the replenishing operation, and as the lay recedes bunter 32 moves away from latch 31 and the transerrer arm and its latch return to their normal positions shown in Fig. 2.

In position XVIII it should be noted that gang LG is again rising, a condition similar to position II, and if shuttle S2 should be depleted the feeler F will again indicate exhaustion when gang LG is fully raised. From this it will be seen that replenishing operations can occur in successive four-pick cycles due to the fact that initiation and effectuation of a replenishing operation is completed within four picks.

Reference has already been made to the longitudinal movement of selector 35. Known mechanisms are available to effect this motion so that bobbins can be drawn from the several stacks in rotation, or from a stack corresponding to the depleted shuttle in box 14. Such controls for the selector form no essential part of the present invention, but it is obvious that the selector should not be moved longitudinally between the time one of the vertical slides is raised and is subsequently depressed.

In the preceding description the rising and falling movements of the actuator lever 43 have been set forth in detail. These movements are derived from cam 59 the roll receiving groove 75 of which has a dwell area corresponding to the neutral position of actuator lever 43, a zone of short radius corresponding to the down motion of lever 43, as in positions I and IX, and a zone of relatively long radius corresponding to up motion of the actuator lever as indicated for instance in positions VII and XV. Cam 50 will be set on the bottom shaft 51 so that the actuator lever 43 will have its movements in the described time relation with respect to the lay and shuttle box gang positions.

From the foregoing it will be seen that the weft detector system and cam 50 are so related that the vertical slides 22-25 will not be raised until relatively late in the four-pick cycle, that is, just before gang LG starts to move down, as for instance in position IX or shortly theretofore. With the train of operations starting this late in the four-pick cycle replenishment can be delayed sufficiently long so that the reserve bobbins will not be placed in the shuttle in box 12 with gang RG up until box 13 is empty and the lay is on front center. It will be seen that this result is accomplished without the use of holding circuits for the electromagnet, or any other storage or holdover means aside from the vertical slides which form a normal part of the multicolor weft replenishing loom. The cam 50 is somewhat different from two-pick cams here-

tofore used for operating lever 43, in that the actuator lever 43 is given a downward motion somewhat earlier than usual. In the usual weft replenishing loom more time elapses between positions VII and IX than described herein. It is found, however, that cam 59 will operate satisfactorily with its high and low points closer together than in the usual cam. Also, cam 50 has a somewhat different angular setting with respect to the loom than usual in that the down motion of lever 43 is effected while the depleted shuttle is on the side of the loom opposite the magazine instead of on the same side.

Having thus described my invention it will be seen that changes and modifications may be made therein by those skilled in the art without departing from the spirit and scope of the invention and I do not wish to be limited to the details herein disclosed, but what I claim is:

1. In a weft replenishing pick and pick loom operating in a replenishing sequence of four successive picks and having a lay with a gang of shifting shuttle boxes at each end thereof, the lay having a weft detector thereon adjacent to one of said gangs to detect weft in a shuttle in said one gang during the first pick of the sequence and the loom having a reserve bobbin magazine adjacent to the other gang provided with a bobbin releaser which when reciprocated releases a reserve bobbin for transfer and is effective during the fourth pick of the sequence to set normally inactive transfer mechanism for subsequent operation by the lay to transfer the released bobbin into the shuttle when the latter is in said other gang, the lay during each pick of the four-pick sequence being successively in bottom, front, top and back center positions, said one gang moving the shuttle into detecting position relatively to the detector when the lay is in the top center position thereof during the first pick of the sequence and holding the shuttle in detecting position until after the third pick of the sequence starts, actuator means for the bobbin releaser, operating means for the actuator means giving the latter a succession of motions in each of two successive two-pick cycles, each succession of motions beginning when the lay is substantially in the bottom center position thereof at the beginning of the first and third picks of the sequence, said operating means causing the actuator means to move in one direction from its neutral position prior to arrival of the lay at the top center position thereof during the first and third picks of the sequence and return to neutral position, and then move in the opposite direction and return to neutral position, a controller normally in noncontrolling position with respect to the actuator, the detector indicating weft exhaustion as long as the shuttle is in detecting position, provided the shuttle is depleted of weft, and means effective to hold the controller in controlling position with respect to the actuator only so long as the detector indicates exhaustion, the controller and actuator means cooperating at the beginning of the second two-pick cycle when the actuator means moves in said one direction to initiate a reciprocation of the bobbin releaser which is completed during the fourth pick of the sequence to effect release of a bobbin from the magazine and setting of the transfer mechanism for operation by the lay.

2. In a weft replenishing pick and pick loom having a lay provided with a gang of shifting shuttle boxes at each end thereof, the loom having a weft detector adjacent one of said gangs

and a reserve bobbin magazine adjacent the other gang provided with a bobbin releaser which when reciprocated effects release of a bobbin from the magazine for transfer and also sets normally inactive transfer mechanism for operation by the lay to transfer the released bobbin, the loom operating in a replenishing sequence of four successive picks during each of which the lay passes successively through bottom, front, top and back center positions, actuator mechanism for the bobbin releaser, a controller normally in noncontrolling position relatively to the actuator, means holding the controller in controlling position with respect to the actuator only so long as the detector indicates weft exhaustion, said detector indicating weft exhaustion when the lay is substantially in the top center position thereof during the first pick of said sequence and continuing to indicate weft exhaustion until the lay reaches the bottom center position thereof in the third pick of said sequence, and operating means for the actuator operating in successive two-pick cycles each of which begins at the start of the first and third picks of the sequence, said operating means causing the actuator at the beginning of each two-pick cycle to move in one direction before the lay reaches the first top center position of the cycle, then return to neutral position, then move in the opposite direction when the lay is on substantially the top center position thereof during the second pick of the cycle, and then return to neutral position, means effective when the detector indicates weft exhaustion to move the controller to controlling position relatively to the actuator during the first pick of the sequence after the actuator has returned to neutral position thereof following movement thereof in said one direction and causing the controller to remain in controlling position until the start of the third pick of the sequence, said actuator and controller cooperating at the beginning of the second two-pick cycle of the actuator, provided the controller is in controlling position, to initiate a reciprocation of the bobbin releaser when the actuator moves in said one direction during the second two-pick cycle and completing said reciprocation of the releaser when the lay is on substantially top center position in the fourth pick of the sequence to effect release of a reserve bobbin and setting of the transfer mechanism.

3. In a weft replenishing pick and pick loom operating in a replenishing sequence of four successive picks and having a lay provided with a gang of shifting shuttle boxes on each end thereof, the lay having a weft detector thereon adjacent to one of said gangs and the loom having a reserve bobbin magazine adjacent to the other gang provided with a bobbin releaser which when reciprocated effects release of a reserve bobbin and sets a normally idle transfer mechanism for operation by the lay, the lay during each pick of the sequence passing successively through bottom, front, top and back center positions, said one gang shifting a shuttle therein toward the detector and causing the latter to indicate weft exhaustion, provided the shuttle is depleted of weft, when the lay is substantially in the top center position thereof in the first pick of said four-pick sequence, said one gang thereafter holding the shuttle in detecting position to cause the detector to continue indication of weft exhaustion until the beginning of the third pick of the sequence, whereupon said one gang moves the shut-

tle away from detecting position and the detector is thereafter incapable of indicating exhaustion during the remainder of the sequence, and control mechanism for the bobbin releaser including an operating cam having a complete cycle of operations every two picks of the loom, said control mechanism including also an actuator operated by the cam and having a succession of movements which starts at the beginning of the first and third picks of the sequence and is effective to cause reciprocation of the bobbin releaser if the detector indicates exhaustion at the beginning of a succession of movements of the actuator, said control mechanism ineffective to reciprocate the bobbin releaser during the first and second picks of the sequence due to the fact that the detector does not indicate exhaustion until after the beginning of the succession of movements corresponding to the first two-pick cycle, and said control mechanism being effective to reciprocate the bobbin releaser during the third and fourth picks of the sequence due to the fact that the weft detector is still giving indication of weft exhaustion at the beginning of the succession of movements corresponding to the second two-pick cycle.

4. In a weft replenishing pick and pick loom having a lay provided with a gang of shifting shuttle boxes at each end thereof, the lay having a weft detector mounted thereon adjacent one of said gangs and the loom having a reserve bobbin magazine adjacent the other gang provided with a bobbin releaser which when reciprocated effects release of a bobbin for transfer and also sets a normally idle transfer mechanism for operation by the lay, the loom operating in a replenishing sequence of four successive picks during each of which the lay starts at bottom center position and then passes successively through front, top and back center positions, said one gang shifting during the first pick of the sequence to move a shuttle therein to detecting position and cause the weft detector to indicate weft exhaustion, provided the shuttle is depleted of weft, when the lay is substantially at the top center position thereof during the first pick of the sequence, said one gang causing the shuttle to remain in detecting position to cause the detector to continue indication of weft exhaustion until after the beginning of the third pick of the sequence, and operating mechanism for the bobbin releaser including a cam which has a complete rotation in two picks of the loom, said operating mechanism including an actuator for the bobbin releaser and a controller for the actuator under control of the detector and normally in non-controlling position, said cam causing the actuator to have an idle two-pick cycle of operations relatively to the bobbin releaser beginning at the start of each of the first and third picks of the sequence, if the controller is in non-controlling position, the actuator being effective to reciprocate the bobbin releaser if the controller is in controlling position at the start of a two-pick cycle, and means causing said controller to move to controlling position with respect to the actuator when the detector indicates exhaustion after the start of the first two-pick cycle and remain in controlling position only so long as the detector indicates weft exhaustion and until the second two-pick cycle has started.

5. In a weft replenishing pick and pick loom having a lay provided with a gang of shifting shuttle boxes at each end thereof, the lay having an electric weft detector thereon adjacent one of

said gangs and the loom having a reserve bobbin magazine adjacent the other gang provided with a bobbin releaser which when reciprocated effects release of a reserve bobbin for transfer and sets a normally idle transfer mechanism for operation by the lay to effect transfer of the released bobbin, the loom operating in a four-pick replenishing sequence during each pick of which the lay starts from a bottom center position and passes successively through front, top and back center positions, said one gang shifting toward the detector as the lay moves from bottom to top center position thereof during the first pick of the sequence and reaching detecting position when the lay is in top center position and thereupon causing the detector to indicate exhaustion if the weft being detected in said gang is depleted, said one gang remaining in detecting position to continue indication of exhaustion by the detector until the beginning of the third pick of the sequence, a cam rotating in two successive two-pick cycles during the sequence, a solenoid, electric means energizing the solenoid only during the time that the detector indicates weft exhaustion, and operating mechanism for the releaser including an actuator operatively connected to the cam and a controller normally in noncontrolling position with respect to the actuator but moved to controlling position relatively to the actuator when the solenoid is energized, said cam causing the actuator to have an idle series of movements during each of said two-pick cycles if the controller is in noncontrolling position at the start of each two-pick cycle but causing the actuator to reciprocate the releaser if the controller is in controlling position at the start of a two-pick cycle, said solenoid holding the controller in controlling position at the start of the second two pick cycle and thereby causing the actuator to reciprocate the releaser if the detector indicates weft exhaustion during the first two-pick cycle.

6. In a weft replenishing loom operating in a replenishing sequence of four successive picks during each of which the lay is successively in bottom, front, top and back center positions and in which a shuttle is in weft detecting position during a detector period extending only from the

time the lay is in top center position in the first pick of the sequence until the lay starts to move away from the bottom center position thereof during the third pick of the sequence, the shuttle thereupon moving away from detecting position and being in transfer position during the fourth pick of the sequence, the loom having an electric weft detector capable of indicating weft exhaustion during said detecting period only, and the loom having also a magazine provided with a bobbin releaser which when reciprocated releases a reserve bobbin for transfer and also sets a normally idle transfer mechanism for a transferring operation, actuating mechanism for the bobbin releaser having two successive two-pick cycles of operation during the sequence, the first and second cycles starting at the beginning of the first and third picks respectively of the sequence, a normally deenergized solenoid, a controller normally in noncontrolling position relatively to the actuating mechanism but being in controlling position relatively thereto when the solenoid is energized, the actuating mechanism, if the controller is in noncontrolling position at the beginning of a cycle and prior to arrival of the lay at its first top center position of the cycle, being ineffective to reciprocate the releaser during the cycle, and electric means causing energization of the solenoid during said detecting period only if the detector indicates exhaustion, whereby the actuating mechanism fails to reciprocate the releaser during the first cycle but does reciprocate the releaser during the second cycle due to the fact that the solenoid remains energized until the beginning of said second cycle.

WALTER H. WAKEFIELD.
